UNITED STATES PATENT OFFICE.

GUSTAV ADOLPH ROEDDE, OF VANCOUVER, CANADA.

DETACHABLE BOOK-COVER.

SPECIFICATION forming part of Letters Patent No. 691,731, dated January 21, 1902.

Application filed March 11, 1901. Serial No. 50,669. (No model.)

To all whom it may concern:

Be it known that I, GUSTAV ADOLPH ROEDDE, a citizen of the Dominion of Canada, residing at Vancouver, in the Province of British Columbia, Canada, have invented a new and useful Temporary Binder, of which the following is a specification.

This invention relates to improvements in that class of temporary binders adapted to be held within cover members to be used for holding magazines or papers; and it primarily seeks to provide an appliance of this character capable of being held within the cover members in such manner that it cannot be readily removed therefrom and which will afford every convenience for handling the papers or books held thereby and in which the said papers and books will be retained in good condition for a subsequent permanent binding; and the said invention consists in the novel construction and peculiar combination of parts hereinafter fully described, and particularly pointed out in the appended claims, reference being had to the accompanying drawings, in which—

Figure 1 is a perspective view of the cover member opened out and the holder secured thereon, one of the binder-bars being in a raised position, the hinged keeper of the lock member being also shown thrown back. Fig. 2 is a detail view of one of the binder or lock bars. Fig. 3 is a cross-section of the casing or box and the lock-bars held therein, and Fig. 4 is a view illustrating my invention as

35 in use.
In the drawings, in which like characters indicate like parts in all the figures, 1 designates an oblong metal casing having a length and width to suit the thickness of paper or 40 magazine to be held thereby and a length approximately that of the cover C, and at the ends at its base it has extensions 1^a, adapted to be bent over the edges of the flexible part C' of the cover and to form locking-clamps 1^a 45 to secure the casing on the cover, as clearly shown in Figs. 1 and 4, whereby to securely hold the casing on the cover and prevent its being easily detached or accidentally separated therefrom.

50 At one end the casing 1 has a transverse pin 2, and at the opposite edge it has a spring-lock 4, the upper face of which lies in a plane

slightly below the upper edges of the sides of the casing, and said upper face is flat, the reason for which will presently appear.

Within the box or casing 1 is held a number (two being shown) of fastener or lock bars, each of which is formed of a thin flexible metal member, the body portion of which is held with its sides in planes parallel with the sides of the casing. One end of each of said bars has a quarter-twist to cause its end to lie in a plane at right angles to the body, and said end is turned to form an eye 3^a to engage the pin 2 to permit the lock-bar swinging upon a vertical plane, as clearly shown in Fig. 1, and the opposite end of the bars is also formed with a quarter-turn to produce a flat extension 3^b, adapted to lie flatwise upon the flat upper face of the lock 4, which includes a hinged keeper 5, adapted to close down over the flat ends 3^a of the bars 3 when it is swung down to its locking position, as shown in Fig. 3, and to facilitate the lifting of the bars 3 when unlocked said ends 3^a terminate in headed portions 3^b, that project beyond the outer end of the lock, as clearly shown in Fig. 4.

From the foregoing description, taken in connection with the drawings, it is thought the manner of operating and the advantages of my invention will be readily understood.

It will be noticed the papers or magazines cannot be removed from the casing or holder without unlocking the bars 3, and the casing will not readily become detached from the cover by reason of the clamps 1^a.

I am aware that box-like members capable of being secured to a cover and having locking-bars disposed longitudinally thereon have heretofore been provided. My invention differentiates, so far as I know, from what has heretofore been provided in this line in the peculiar correlation of the casing with the cover, the axial pin in one end, the lock having a flat top at the other, and the peculiar form of lock-bars that coöperate with the axial pin and the lock.

Having thus described my invention, what I claim, and desire to secure by Letters Patent, is—

1. A temporary binder, comprising in combination with a book-cover, a U-shaped casing extended lengthwise of the foldable part of the cover, said casing having extensions

- 1^a, at the opposite ends adapted to clamp over the edges of the cover, locking-bars, pivotally mounted in the upper edge of one end of the U-shaped casing to swing in a vertical plane, 5 a lock 4 in the opposite end of the casing, said lock including a flat bearing-surface, and a hinged keeper adapted to close down over said flat bearing-surface, the locking-bars having their free ends flattened to flatwise 10 engage the said flat surface of the lock, all being arranged substantially as shown and for the purposes described.
2. A temporary binder, comprising in combination, with a book-cover, a U-shaped casing 15 extended longitudinally on the foldable part of the cover, locking-bars pivotally mounted on one end of the casing to swing

upward in a vertical plane, a lock device in the other end of the casing for securing the free ends of the locking-bars to their closed position, said casing having bendable extensions at the ends adapted to clamp over the outer edges of the cover, whereby to hold the casing from separating accidentally from the cover, all being arranged substantially as 20 shown and for the purposes described. 25

In testimony whereof I have hereunto signed my name to this specification in the presence of two subscribing witnesses.

GUSTAV ADOLPH ROEDDE.
